UNITED STATES PATENT OFFICE

ASHUR U. WETHERBEE, OF CHICAGO, ILLINOIS

BOILER

Application filed February 25, 1925. Serial No. 11,389.

My invention has reference to water-tube boilers of the Stirling type, that is, a ring circuit boiler in which four main drums forming a quadrupole series of drums, are arranged in series communication through interposed banks of tubes with a lower bank over the fire box so that the gases of the gas-current first pass substantially crosswise thereof, the two lower drums being placed with the one in front only slightly above the one or mud drum in rear thereof or at a relatively low level, so that the lower bank of tubes run at a slight inclination sufficient to cause circulation and are substantially at right angles to the flow of the gases from the furnace grate or other heating source, and of such a length as to insure that they will be entirely, or fully and completely exposed to the hot gases.

The invention also embodies a novel arrangement of drums in quadrangular relation and including upper steam and water drums, a lower front water drum and a still lower rearward mud drum related to each other in a novel manner and interconnected by a novel arrangement of tubes or banks of tubes with a novel arrangement of baffles or baffle walls and a superheater of novel arrangement whereby maximum steam generating efficiency with a minimum of fuel consumption together with the production of drier steam, greater steaming capacity and economical manufacture is provided for, although it is to be understood that a great latitude is allowed in the exact arrangement of the parts including the superheater and baffles referred to.

By way of explanation, it is pointed out that existing water tube boilers are commonly divided into two general classes, bent and straight tube boilers. Each class has its advantages, and the object of this invention is to combine the important advantages of both types, while eliminating as far as possible the important disadvantages of both.

This invention is a boiler of the bent tube class, thus securing the advantages of low first cost, and low cost of repairs and maintenance, and inherent ease of inspection,

while eliminating the high first cost and high cost of maintenance of the straight tube class of boilers, for hand holes, gaskets, etc. In the present state of the art of furnace design and construction, the length of those tubes exposed to radiant heat would be so proportioned as to maintain the furnace temperature within such limits as would not be destructive to the furnace linings.

With the above and other objects in view, I have illustrated in the accompanying drawing, forming a part of this specification, a practical and preferred embodiment of the invention illustrating its operating principles and constructional features, in which the figure is a vertical sectional view, partly in elevation, of a water tube steam generator or boiler constituting my invention, the setting or wall structure thereof being in section.

By reference to the drawing, it will be noted that the setting or wall structure 10 includes the front wall 11 and the rear wall 12. A suitable heating means or source is provided and shown partly beneath the horizontal wall 13 at the front portion of the furnace setting such as a coal burning fire box and grate or other suitable fuel burner, either coal or oil or gas, but which, in the present instance, is shown as an endless grate member 14 trained over a roller 15 and provided for gradual rearward feeding and burning of the fuel thereon, and from which the generated heated gases and products of combustion pass upwardly through the setting.

A lower or mud drum 16 is arranged across the furnace near the rear wall thereof, but slightly spaced therefrom, and above the fire wall 17 of the furnace or boiler setting as clearly seen in the drawing.

A water drum 18 is arranged to project partly into the front wall 11 but not in contact therewith, being separated by a packing 19 in a circular recess cut in said wall to allow movement of said drum due to expansion which recess or cavity receives the water receiving drum 18 which is disposed slightly above the lower or mud drum 16. Adjacent

the reinforced top wall or cover 20 of the boiler structure or furnace setting are front and rear steam and water drums 21 and 22, said drums being placed substantially at the 5 same level, that is, having a common center on a horizontal plane but the former being preferably slightly larger than the latter and constituting the principal steam and water receiving drum. These drums, 21 and 10 22, are spaced apart horizontally, the drum 21 being spaced from the front wall 11 and disposed completely rearwardly of the water drum 18 and forwardly of the lower or mud drum 16 but in a vertical plane closer to the 15 drum 18 than to the drum 16, whereas the drum 22 is disposed substantially directly above the drum 16, that is, with their centers substantially in the same vertical plane.

A lower set or bank of tubes 23 extends 20 between the lower front portion of the mud drum 16 and the lower rear portion of the water drum 18, these tubes being arranged at a slight upward inclination forwardly, shown in the drawing as about 12 to 15 degrees but comparatively or substantially 25 horizontal. This inclination may be varied. That is, these tubes are arranged at a slight inclination from the horizontal to be exposed to the radiant heat of the fire and so 30 that the hot gases from the furnace fire box pass the same substantially at right angles, that is, normal or perpendicular to their axes, this crosswise flow of the gas current for the first pass of gases securing the advantage 35 of better heat transfer due to the direct impingement of the hot particles of the gases and products of combustion on the tubes, the scouring off of the gas film which tends to cling to the tubes, and the mixing 40 of these gases during their flow between and around the tubes. This is analogous to the passage of the gases through the first pass of the common type of nearly horizontal straight tube boilers, and eliminates the 45 tendency for the gases to "lane" through the center of the gas passages when the gas passes parallel to the tubes in many water tube boilers. It is further to be noticed and pointed out that the lower bank of tubes 23 50 subjected to radiant heat, is unobstructed by baffles or baffle walls so that the full lengths thereof are exposed to the radiant heat and heated gases or products of combustion from the fire, as well as the lower drums at the 55 portions to which the tube ends are connected, the gases taking a tortuous passage between and around the tubes when hottest, in addition to exposing the tubes to the radiant heat of the fire.

60 In addition to the radiant heat bank or upflow water tubes 23, connecting the drums 16 and 18, the water drum 18 is connected to the upper steam and water drum 21 by means of an upper upflow bank of water and 65 steam tubes 24 which extends from the up-

per portion of the water drum 18 to the lower portion of the steam and water drum 21 and are inclined upwardly and rearwardly slightly, being disposed substantially vertically as shown and subjected to the action 70 of the hot gases after passing from the lower bank of water tubes 23 in conjunction with suitable baffle walls which may be employed to cause the gases to traverse or be forced to pass partly or wholly crosswise of said upper 75 bank 24 as will be hereinafter more particularly described.

A downflow bank of water tubes 25 extends between the lower rear portion of the drum 21 and the upper forward portion of the 80 drum 16, and one of these tubes or a series thereof, that is, the lower row or rows, may be bent in angular relation as indicated at 85 26 or to extend substantially downwardly in a vertical direction at their upper portions from the drum 21 and then in an inclined direction rearwardly to the drum 16 spaced 90 from the tubes 25 and in triangular spaced relation with respect thereto. It is also to be noted that the arrangement of the drums 16, 18 and 21 in triangular relation, as distinct from the quadrangular relation of the drums 16, 18, 21 and 22, also provides for the triangular arrangement of the 95 banks of tubes 23, 24 and 25, which banks 100 form the sides of the triangle connecting the corners formed by the drums 16, 18 and 21, thus providing an intervening or intermediate space 27 between the tubes 23, 24 and 26 or 25 if the tubes 26 bent as described 105 are omitted, and also a space 28 between the tubes 25 and 26 in case the latter angular tubes are employed as described.

A further set or bank of tubes is designated at 29 and extends between the upper 110 rear portion of the mud drum 16 and the bottom or lowest portion of the steam and water drum 22. These tubes are preferably slightly inclined forwardly but of less inclination than the tubes of the bank 25 of the downflow set, and may be vertical if desired, and constitute a further set or series of downflow tubes for water, but from which the steam which is liberated therefrom rises or flows upwardly at and into the steam and 115 water drum 22. This latter drum terminates in spaced relation to the rear or back wall 12 of the setting to provide an outlet port or breeching 30 to the smokestack at the rear of the setting and with which cooperates a control valve or damper 31. Feed 120 water flows down tubes 29.

The upper drums, 21 and 22, are connected by curved upper and lower series of tubes 32 and 33, the upper tubes 32 providing for the passage of steam liberated in the drum 21 to the drum 22, where the moisture carried over with this steam is deposited, and almost dry steam passes out through the pipe 125 connection or steam nozzle 34 for use. The 130

lower series of tubes 33, as distinguished from the upper series 32, are provided to secure equalization of water level between the respective drums 21 and 22. It may also be pointed out that the lower bank 23 is preferably shorter than or about the same length as bank 24 and that the location of the tubes 26 for supporting a baffle between the spaces 27 and 28, as will be later described, may be varied as desired, and the use thereof is also optional. There is little difference between the levels of the two lower drums, the difference in level being just enough to cause circulation.

The drum 21 is disposed between drums 16 and 18 and has its axis substantially in the vertical plane of the center of gravity of the ring circuit structure, as illustrated, so that this structure, comprising the drums 20 and tubes and baffles, is thus suspended in proper position and without any appreciable tendency to rock or tip either forwardly or rearwardly. The drum 22 and the bank of tubes 29 connecting it to drum 16, act as anchor or stabilizing means to hold the ring circuit structure against tilting movement, as will be clear from the drawing, this means being highly effective in this respect due to the positioning of drum 21 between drums 16 and 18, above described.

The space 27 provides accommodation for a superheater 35 of any preferred or well known type. It will be apparent that the superheater is in the path of the gases immediately after passing through the lower bank of tubes designated at 23, where the temperature of the gases is very high. This serves to reduce the size and first cost of the superheater to the minimum, but where the gas temperature is sufficiently reduced so as to avoid danger of burning the superheater. This location of the superheater is very favorable to the securing of the very high degrees of superheat now coming into general practice, and is equivalent to that secured by the drop header or omitted tube type of nearly horizontal straight tube boilers, which has proven so advantageous that it has been generally adopted in spite of the increased expense.

In connection with the arrangement of the tubes, drums and superheater as described, a novel arrangement of baffles or baffle walls is provided. The row of tubes 26 forms means for supporting a similarly inclined first baffle 38, which extends from the lower or mud drum 16 upwardly along the top portions of the tubes 26, which latter are well separated from the tubes 25 and so arranged to partially support the baffle. This exposes the bottom of the tube or row of tubes 26 to the comparatively hot gases between the first and second banks of tubes 23 and 24 respectively, and as the baffle 38 terminates above the bent portion

of the tube 26, an escape passage is provided between the upper end thereof and the drum 21 so that the top of the tube 26 is exposed to the gases passing between the second and third banks of tubes 24 and 25 respectively. It is here pointed out that the tube or row of tubes 26 can be placed parallel to either the second or third banks of tubes and the baffling arranged in any other suitable manner, but the same is here shown provided with a baffle wall 39 extending partially across the bank 24 from the upper end of the baffle 38 and with a rearward baffle 40 extending to the bank 25 and suitably supported as by means of a bracket or other suitable device 41 attached to the lower tubes of the bank 25. These baffles 39 and 40 branch out in diverging relation as shown so that after passing around the superheater 35, the hot gases pass through the next bank of tubes 24, being preferably forced to pass partly or wholly crosswise, as shown, and by means of the baffle 39, but in certain sizes or proportions, not shown, passing parallel to these tubes, in which case the baffle 39 is made shorter or entirely omitted. It will thus be apparent that the gases will traverse the tubes of the bank 24 twice, first forwardly and then rearwardly across the lower and upper portions thereof respectively, after which, the gases are caused by the baffles 39 and 40 to enter and partially pass the tubes of the bank 25 or third bank of tubes, at right angles thereto. At this point, the gases are caused to pass downwardly along the tubes 25 by means of a baffle 42 on the upper side thereof and extending between the drum 21 and a point in spaced relation to the lower or mud drum 16, at which point a baffle plate or wall in the form of a partition 43, is extended between the lower end of the baffle 42 and the adjacent portion of the tube bank 29, being supported from the baffle 42 as indicated at 44 and from the forward tubes of the bank 29 by means of the bracket or other device 45 attached thereto as shown, or otherwise as desired or as is common practice in the art. In some cases, not shown, the tubes 25 may be cross baffled to secure three crosswise passes around the tubes 25, though it is to be understood that the gases after passing over the baffle 40 and entering the tubes 25 at right angles thereto, will be caused to again cross the tubes 25 forwardly toward the baffle 38 and then cross the tubes 25 to exist at approximately right angles into the last bank of tubes 29 at the lower portion thereof, with the construction disclosed, thus securing approximately the same result as if an additional baffle was provided across the tubes 25. It may also be pointed out that the use of the baffle 39 is optional, and that the space between the bank 24 and the front wall 11 of the setting, 130

may be employed for receiving a superheater in lieu of or in addition to the use of the superheater 35. After passing the passage below the baffle 43; the gases then 5 pass upwardly along and substantially parallel to the tubes of the bank 29 adjacent the rear wall 12 of the setting. However, the tubes 29 may be and preferably are partially cross baffled to similarly affect the gases 10 as shown, to secure better contact with these tubes, and secure a greater heat extraction when sufficient suction is available, or may pass parallel to the tubes when less draft is available. For this purpose, a cross baffle 15 46 may be provided at the rear portion of the tubes 29, substantially horizontally and intermediately of the lengths or upper and lower ends thereof, but preferably nearer the upper ends of the tubes 29 and the adjacent drum 22, while the rear wall 12 may 20 be provided with an inwardly extending horizontal ledge or shoulder 47 supporting a short baffle wall 48 in conjunction with the adjacent outer or rear end of the baffle 46, the baffle 48 extending inwardly from the wall 12 to throw the fire gases towards the tubes 29 and prevent the same from passing up between the wall and the baffle 45 or rear tubes of the bank 29, during their upward passage to the smoke exit 30. In this manner, the gases are, therefore, caused to be deflected forwardly across the tubes 29 by the baffles 46 and 48, instead of "laning" 25 along parallel to the tubes 29 the full lengths thereof, said gases after passing into the space between the banks 25 and 29 then passing rearwardly across the tubes 29 above the baffle 46 and finally out the smoke exit. However, during this action, said gases will 30 act upon the tubes 32 and 33 and the upper drums, to secure greater efficiency.

Feed water is preferably introduced into the upper drum 22 through a feed water pipe 49, either from the main or a feed 45 water pre-heater, so that the comparatively cold feed water passing down through the bank of tubes 29 will be absorbing the heat from the gases just before their exit, and gain a higher thermal head at this point, 50 thus absorbing a greater total amount of heat from these gases and gaining some of the advantages of an economizer. Thus, it will appear that the bank of tubes 29 serve an economizer function. As shown, the 55 lower or mud drum 16 is also provided with a clean-out or blow-off 50 for cleaning out the mud drum and system, and said pipe may be provided with a suitable shut off valve as indicated.

This boiler has the advantages of the straight tube boilers in exposing more or less length of the bottom row of tubes to absorption of radiant heat from the fuel bed of its equivalent, this amount being varied 60 by varying the distance between the lower

drums, thus varying the length of these lower tubes. In the present state of the art of furnace design and construction, the length of these tubes exposed to radiant heat would be so proportioned as to maintain 70 the furnace temperature within such limits as would not be destructive to the furnace linings. Furthermore, the number of tubes shown in any or all of the banks may be varied to meet various conditions, but the 75 respective areas for the passage of steam and water in each of these banks should be such as to cause no restriction to their passage and give a free circulation for the liberation of steam, and its rapid removal from the interior of the heating surface at all 80 rates of evaporation. The tubes 26 serve as an element of the boiler, in addition to supporting the baffle 38.

The drum 21 is preferably disposed back 85 of the drum 18 so as to leave a space 60 in which an additional superheater 61 is disposed. The superheater 61 may be employed to great advantage as an interstage heater for turbines. If desired the superheater 61 may be employed as the primary 90 superheater of the boiler. Its position, i. e., between the second bank 24 of tubes and front wall 11 makes it admirably adaptable to use as an interstage heater:

This superheater 61 comprises the hairpin shaped tubes 62 connected to manifolds 63 and 64 for intake and discharge of steam respectively. Suitable flanged nozzles 65 and 66 are connected to the manifolds 63 and 64 respectively for connection between stages of a turbine or between a high pressure and a low pressure turbine, which have not been shown because they are well understood by those skilled in the art and form 100 no part of my invention.

The operation of the device as shown and described is as follows; water is fed into or supplied to the drums through the feed water pipe 49 into the drum 22 or otherwise, as desired, until the water level reaches the normal water level ordinarily employed, which is approximately slightly below the centers of the drums 21 and 22 as indicated. Water being present in all of the drums and the banks of tubes connecting the same, the heat from the fire bed is brought into action by the gases passing or flowing upwardly from the burner across the tubes of the bank 23 and around the other banks of tubes and baffles or baffle walls in a manner indicated by the curved arrows in the drawings. The straight arrows indicate the direction of flow of the water in the tubes from the respective drums or headers. The gases, products of combustion and smoke escape out through the smoke exit or flue 30 through the stack or flue. The gases, after passing the tubes of the bank 23, may pass over the superheater 35 as shown to dry the 110

steam which has been previously generated and passed therein by connection with the drum 22, from which it may be drawn off as indicated in dotted lines in the drawings 5 for use in a dry efficient form or this super-heater may be omitted. The gases are caused by the baffles 38 and 39 to pass across the tubes of the bank 24 toward the front wall 11 and then rearwardly over the upper 10 portions of said tube above the baffle 38 and the baffles 39 and 40 across the upper portions of the tubes of the bank 25 rearwardly and then downwardly along the same and then rearwardly beneath the baffles 42 and 15 43. The gases then pass rearwardly across the tubes of the bank 29 and are deflected forwardly across said tubes in an opposite direction by the baffles 46 and 48, subsequently passing rearwardly across the upper 20 portions thereof and out the smoke exit 30. As the water in the tubes 23 is heated, it flows upwardly through the same and into the water drum 18, and then upwardly through said drum and the tubes 24 into the 25 drum 21, where such portion as has become steam, is liberated and flows through the tubes 32 into the drum 22. The residue of the water in the drum 21 flows down through the tubes 25 through the mud drum 16, to 30 again flow through the tubes 23, as before, with an addition thereto of sufficient fresh water from the drum 22 which is kept supplied by the feed water pipe, pre-heated or not, as indicated at 49, through the tubes 35 29. During the downflow of the water in the tubes 29, the same becomes pre-heated so that said bank of tubes acts as an economizer, extracting the heat from the gases immediately prior to their exit at 30. As 40 previously stated, the steam may be drawn off from the drum 22 by the connection 34 or superheated in the superheater 35, as required generally in high pressure practice. Furthermore, any water which is carried 45 over in the tubes 32 from the drum or header 21 to the header 22 is either generated into steam or discharges into the header or drum 22 and finally circulates in the ring circuit boiler arrangement described for the generation of steam. The flow in the tubes 26, 50 may correspond with the flow in the tubes 25 or may be upward according to the arrangement and location thereof. Moreover, they are subjected to the action of the gases 55 beneath the baffle 38 after passing the superheater 35 and also after passing forwardly over the tubes 24, in passing rearwardly across the top portions of said tubes across the baffles 38, 39 and 40 prior to entering 60 the upper portions of the tubes 25. This construction and arrangement gives high steam generating capacity with a minimum of fuel consumption.

If desired the steam discharge nozzle 34 65 may be mounted on drum 21 for the dis-

charge of steam therefrom. The groups of tubes 32 and 33 or either of them may also be omitted if desired, depending upon the tubes 25 and 29 and drum 16 for equalization.

While I have now described the form of the invention which I now consider to be the preferred embodiment, it is to be understood that various alterations in the arrangements of the parts and form and construction thereof, may be made so long as the same do not depart from the spirit and scope of the invention as defined in the claims appended hereto.

I claim:

1. In combination, a boiler casing having a front wall, a boiler in said casing comprising a mud drum at the back of the casing, a water drum slightly above the mud drum and disposed at the forward side of the casing and sealed with the front wall, a steam and water drum disposed at a higher level than the water drum and between the water drum and the mud drum, tubes connecting said three drums in a ring circuit, a furnace in the lower part of the casing, the tubes joining the mud drum and water drum being inclined at a small angle to the horizontal to provide circulation, the length of said tubes being proportioned to the capacity of the furnace so that the fire gases flowing from the furnace strike across said tubes and fill the entire space through which said tubes are projected, and a baffle disposed above the lower tubes so as to provide a relatively large gas space above said tubes along their full length, and a bent tube type of superheater disposed in the aforesaid gas space substantially parallel to the lowermost bank of tubes.

2. In combination, a boiler casing having a front wall, a boiler in said casing comprising a mud drum at the back of the casing, a water drum slightly above the mud drum and disposed at the forward side of the casing and sealed with the front wall, a steam and water drum disposed at a higher level than the water drum and between the water drum and the mud drum, tubes connecting said three drums in a ring circuit, a furnace in the lower part of the casing, the tubes joining the mud drum and water drum being inclined at a small angle to the horizontal to provide circulation, the length of said tubes being proportioned to the capacity of the furnace so that the fire gases flowing from the furnace strike across said tubes and fill the entire space through which said tubes are projected, and a baffle disposed above the lower tubes so as to provide a relatively large gas space above said tubes along their full length, a cross baffle extending from said first baffle transversely to the tubes joining the water drum and the steam drum to cause the gases to make two

cross passes with respect to said latter tubes, and an interstage superheater disposed in the space above the water drum and between the latter tubes and the front wall of the 5 casing.

3. In combination, a boiler casing having a front wall, a boiler in said casing comprising a mud drum at the back of the casing, a water drum above the mud drum and adjacent the front of the casing, and a steam and water drum above and between the water drum and the mud drum, banks of tubes connecting the drums in a ring circuit, the tubes connecting the water drum to the 10 water and steam drum being inclined upwardly and rearwardly of the casing, a series of tubes connecting the mud drum and the steam and water drum, the tubes of said series being disposed in the space enclosed by the banks of tubes and being inclined oppositely to the bank of tubes connecting the water drum to the steam and water drum, and a baffle supported by the tubes of said series and extending upwardly from the mud drum, said baffle terminating short of the steam and water drum.

4. In combination, a boiler casing having a front wall, a boiler in said casing comprising a mud drum at the back of the casing, a 20 water drum above the mud drum and adjacent the front of the casing, and a steam and water drum above and between the water drum and the mud drum, banks of tubes connecting the drums in a ring circuit, the tubes connecting the water drum to the steam and water drum being inclined upwardly and rearwardly away from the front wall of the casing, a superheater disposed between the front wall of the casing 25 and the bank of tubes connecting said water drum to the steam and water drum, a series of tubes connecting the mud drum and the steam and water drum and inclined upwardly and forwardly of the casing, said series of tubes being disposed in the space enclosed by the banks of tubes, and a baffle supported by the tubes of said series and extending upwardly from the mud drum, said baffle terminating short of the steam and water drum.

5. In combination, a boiler casing having a front wall, a boiler in said casing comprising a mud drum at the back of the casing, a water drum above the mud drum and adjacent the front of the casing, and a steam and water drum above and between the water drum and the mud drum, banks of tubes connecting the drums in a ring circuit, the tubes connecting the water drum 55 to the water and steam drum being inclined upwardly and rearwardly of the casing, a series of tubes connecting the mud drum and the steam and water drum, the tubes of said series being disposed in the space enclosed by the banks of tubes and being in-

clined oppositely to the bank of tubes connecting the water drum to the steam and water drum, and a baffle supported by the tubes of said series and extending upwardly from the mud drum, said baffle resting upon the upper surfaces of the tubes and terminating short of the steam and water drum. 70

6. In combination, a boiler casing having a front wall, a boiler in said casing comprising a mud drum at the back of the casing, a water drum above the mud drum and adjacent the front of the casing, and a steam and water drum above and between the water drum and the mud drum, banks of tubes connecting the drums in a ring circuit, the tubes connecting the water drum to the steam and water drum being inclined upwardly and rearwardly away from the front wall of the casing, a series of tubes connecting the mud drum and the steam and water drum and inclined upwardly and forwardly of the casing, said series of tubes being disposed in the space enclosed by the banks of tubes, a baffle supported by the tubes of said series and extending upwardly from the mud drum, said baffle terminating short of the steam and water drum, and a superheater disposed beneath the baffle and between said series of tubes and the bank of tubes connecting the mud drum and the 80 water drum. 85

7. In combination, a boiler casing, a boiler comprising a mud drum, a water drum, and a steam and water drum disposed in substantially triangular arrangement, the steam and water drum being above and between the mud drum and the water drum, banks of tubes connecting the drums in a ring circuit and enclosing a substantially triangular space, a series of tubes disposed in said space 100 and connecting the mud drum and the steam and water drum, the lower portions of the tubes of said series being inclined oppositely to and extending toward the tubes of the bank connecting the water drum to the steam and water drum, and a baffle supported by the tubes of said series and extending upwardly from the mud drum, said baffle terminating short of the steam and water drum. 105

8. In combination, a boiler casing having a front wall, a boiler comprising a mud drum adjacent the back of the casing, a water drum above the mud drum and adjacent the front wall of the casing, and a steam and water drum above and between the mud drum and the water drum, banks of tubes connecting the drums in a ring circuit, said banks of tubes enclosing a substantially triangular space and the tubes of the bank connecting the water drum to the steam and water drum being inclined upwardly and rearwardly of the casing, a series of tubes disposed in said space and having their lower portions inclined upwardly and forwardly of the casing, and a main baffle sup- 115 120 125 130

ported by said series of tubes and extending upwardly from the mud drum, said baffle terminating short of the steam and water drum and being spaced an appreciable distance above the lower bank of tubes connecting the mud drum and the water drum thus providing a space of appreciable height above said lower bank of tubes facilitating flow of the products of combustion from the furnace transversely of the tubes of the lower bank.

9. In combination, a boiler casing, a boiler comprising a mud drum, a water drum, and a steam and water drum disposed in substantially triangular arrangement, the steam and water drum being above and between the mud drum and the water drum, banks of tubes connecting the drums in a ring circuit and constituting a ring circuit structure enclosing a substantially triangular space, said mud drum and the water drum being disposed below the center of gravity of said structure, a series of tubes disposed in said space and connecting the mud drum and the steam and water drum, the lower portions of the tubes of said series being inclined oppositely to and extending toward the tubes of the bank connecting the water drum to the steam and water drum, and a baffle supported by the tubes of said series and extending upwardly from the mud drum, said baffle terminating short of the steam and water drum.

In witness whereof, I hereunto subscribe my name this 21st day of February, 1925.
ASHUR U. WETHERBEE.
